SELF PROPELLED TOY

Blair W. Gibson, 3142 Buena Vista Terrace,
Washington, D.C.

Filed Dec. 2, 1958, Ser. No. 777,658

3 Claims. (Cl. 46—243)

My invention pertains to amusement devices for children particularly in the nature of self propelled toys that can be easily operated and manipulated to obtain diverse and unexpected effects much to the amusement of the child.

Toys of the self propelled type are widely known. Many employ spring wound motors, others bands of an elastic nature or even electric motors to provide mobility to such toys. Obviously toys of the self propelled type are based either on the wheel or sphere principles by which they can traverse a surface. The customary means to connect the toy with the power source in appropriate cases is to use a gear train between it and the power source, which in some manner will roll or wheel the toy along a surface. The mode of travel in some cases is controllable and a preselected path either circular or linear can be realized. Moreover toys of this type have concealed within their shape a means for starting and stopping the motor.

In the operation of the motor, various ancillary effects can be provided to give a variety of movements either of the rhythmic or spastic type which of course adds to the enjoyment of the toy by the child.

However, most toys of the self propelled type lack control over their movements. Generally they run only in preselected paths which cannot be varied to give other paths of travel. Normally they are not controllable by the child and for this reason something more is desired in toys of this type to give additional and complete satisfaction to the child.

It therefore is an object of my invention to provide a self propelled toy of the class described that is controllable at the will of the child.

A further object of my invention is to provide a toy of the type described whose path of travel can be changed while in motion at the will of the child operating it.

A still further object of my invention is to provide a self propelled toy of the type described wherein the motive power can be applied independently to either wheel or to none and still give various gyrations and spastic effects when the motor is in operation, and at the will of the child.

Another but not final object of my invention is to provide a toy of the split wheel self propelled type wherein the rate of travel of each wheel can be adjusted to obtain various unexpected results much to the amusement and surprise of the child.

These and other objects will become apparent to those skilled in this art particularly in view of the clear and definitive description given hereinbelow of the fundamental principles underlying my invention which are applied in connection with disclosure of a preferred modification and further illustrated in the attached drawings forming a part of this disclosure.

In the drawings:

Figure 1 is a perspective view of my self propelled type.
Figure 2 is a vertical section.

2

Figure 3 is a section taken along line 3—3 of Figure 2, while

Figure 4 is an enlarged fragmentary section taken along line 4—4 of Figure 2.

5 My improved self propelled toy shown in its preferred modification as described hereinbelow consists of a tubular shell 10 consisting of two sections 12 and 14. These are mounted in a spaced apart parallel relationship on a shaft 16. The shaft is suitably journaled in the conical projections 18 and 20 that are axially located on the respective interior faces 22 and 24 of the sections 12 and 14.

The tubular shell sections 12 and 14 have one end thereof closed while the other end is open and faces the open end of the other section thereby creating between

15 a cavity within which is housed the motion making mechanism. Each section 12 or 14 is generally U-shape in cross section, and each having a web 26 and 28 respectively. From the circular rims of the said webs 26 and

20 28 depend circular flanges 30 and 32 respectively. Around the periphery of each of said flanges 30 and 32 adjacent to the edge of the respective web portions 26 and 28 are disposed collars 34 and 36. The collars 34 and 36 act as the rims 38 and 40 for the tubular sections 12 and 14 to form solid web wheel members 42 and 44.

25 The solid web wheel members 42 and 44 have hubs 46 and 48 of which the conical extensions 18 and 20 are a part. As mentioned previously, the shaft 16 maintains the freely rotatable wheels 42 and 44 in a spaced apart parallel relationship whereby the wheels can move independently of each other. Between the two sections 12 and 14 there is provided a space 50 for this purpose. The ends of the shaft 16 support the said wheels which are in a freely rotatable condition.

30 35 At an intermediate point between the said conical extensions 18 and 20, the mechanism for propelling and controlling the movement of the toy is suspended from the shaft 16 by means of arms 54 that support the saddle 52 in which the mechanism is seated. The saddle 52 is made of a strip of metal or some other suitable material as desired into an open shaped container to hold the motor 58 and the battery cell 60 which is the source of energy of motion making device.

40 45 The motor 58 has an upright shaft on which is mounted fixedly a pinion gear 62, which in turn drives the larger diameter bevel gear 64 with which it is in an intermeshing tooth relationship. The larger bevel gear 64 as well as the spur gear 68 is mounted fixedly on a common shaft 50 66 which is journaled within the arms 54 whereby a further reduction in the speed of the motor can be realized. In turn the spur gear 68 drives the larger gear 70 that is fixedly mounted on the shaft 16 and drives the same energy of the motion making device.

55 The shaft 16 consists of two elongated circular sections 72 and 74. They are preferably made of electrically conductive metal since they are a part of the electrical circuitry involved in this toy. One of the sections 72 60 may be a solid rod while the other 74 is preferably of a tubular construction for reasons described further. The ends of the shaft sections 72 and 74 are connected together with a connector sleeve 76 which is frictionally engaged about the ends of the said sections. In event 65 it is desirable to rotate one section and retain the other section motionless then the shaft section will slip within the embrace of the connector sleeve 76.

The outer ends of the shaft sections 72 and 74 protrude beyond the faces of sections 12 and 14 and have 70 thereon threads 78 with which to engage on one end a capped nut 80 and on the other end a knurled nut 86. Positioned on the inner side of the hubs 46 and

48 respectively are collars 82 and 84 respectively with which the hubs can be in abutting relationship when the nuts 80 and 86 are turned inwardly to the faces of the wheels 42 and 44. The wheels are thus engaged frictionally by the nut and collar and will rotate with the shaft 16 if the latter is in motion. When disengaged the wheel is freely rotatable. Thus by proper adjustment one or both wheels can be engaged by the friction clutch about each hub to any desired degree to provide any desired degree of motion and rate to each wheel.

Thus by proper adjustment the child can have the toy run in a circle or run longitudinally. Likewise by having the device in a slippable wheeling condition, the motor on the saddle will rotate about the shaft 16 and cause the toy to move in a spasmodic way which is unpredictable and yet amusing. Though not illustrated I may mount suitable figurines of people, animals and other characters on the saddle or shaft or otherwise conceal the nature of the mechanism by proper adornment which will not interfere with the function of the device.

To maintain the saddle 52 within the central part of the cavity 88 between the sections 12 and 14, I provide on the shaft 16 suitable guides 110 about one of the arms 54 which prevent the arms from moving laterally on the shaft 16. However it should be noted that the arm 54 is also freely rotatable.

I also provide a means to control the flow of electricity from the battery 60 to the motor 58. Within the tubular section 74 of the shaft 16 there is a rod 90 whose end 92 extends within the bore 94 of the connector sleeve 76. This end is in almost contacting relationship with the end of the section 72 and also joined by the connector sleeve 76 to form the shaft 16. Both sections 72 and 74 are made of an electrically conductive material such as metal or copper but separated by the non-conductive connector sleeve 76. The end 96 of the rod 90 terminates into a push-pull snap type of switch by which the contact made between the two ends completes the circuit for electricity to flow into. To provide for the flow of the electric current, I use a commutator ring 100 which is in slidable rotary contact with the shaft section 72. This is connected to the usual binding post 104 by means of a wire 102. The other binding post on the motor 58 is connected to the battery 60. The battery is grounded to the arm of the saddle. Thus electricity will flow when the switch 98 is pushed inwardly.

Obviously the wheel sections can be made of various materials. Clear plastics such as methacrylates and others can be used. Likewise any of the other components may be made of desired materials just as long as they perform the intended function.

Though as indicated previously the disclosure is directed to the preferred embodiment of my invention and

should not be construed as limitation of the principles underlying my invention except as defined by the hereunto appended claims.

I claim:

5 1. A self propelled toy comprising a pair of closed end tubular wheels, said wheels mounted rotatably in a spaced apart parallel relationship respectively on the ends of a driven shaft, the said driven shaft comprising at least two axially aligned portions frictionally engaged with each other, a friction clutch means on at least one end of the said driven shaft acting on at least one of the hubs of said wheels, a motor means suspended from said shaft, a power transmission means connecting said motor means and at least one of said axially aligned portions of said shaft, and a means to control said motor means.

10 2. A self propelled toy comprising a pair of closed end tubular wheels, a mechanism housing cavity formed within the said tubular wheels, a shaft adapted to maintain said wheels in a spaced apart rotatable parallel relationship, the said shaft comprising at least two co-axially aligned portions, a friction clutch on one of the said axially aligned portions of said shaft adapted to engage each wheel independently, a motor means suspended from said shaft adapted to rotate one of the said co-axially aligned portions of said shaft, a gear train connecting the said shaft and said motor means and a means to control said motor.

15 3. A self propelled toy comprising a pair of closed end tubular wheels, a mechanism housing cavity formed within the open ends of said wheels, a shaft adapted to maintain said wheels in a spaced apart rotatable relationship, the said shaft comprising two axially aligned electrically conductive portions, a connector between the said sections adapted to maintain said portions in a spaced apart coaxial alignment and electrical disconnection, a means within one of said portions to contact the other portion within the said connector, a means to conduct electricity to each of said shaft portions, an electric motor power means suspended from said shaft adapted to rotate said shaft, a friction clutch on the outer end of each of said portions adapted to engage the hub of the tubular wheel and a means for moving the said means within said one portion to control flow of electrical current to said motor disposed on the said end of said one of said shaft portions.

20 4. A self propelled toy comprising a pair of closed end tubular wheels, a mechanism housing cavity formed within the said tubular wheels, a shaft adapted to maintain said wheels in a spaced apart rotatable parallel relationship, the said shaft comprising at least two co-axially aligned portions, a friction clutch on one of the said axially aligned portions of said shaft adapted to engage each wheel independently, a motor means suspended from said shaft adapted to rotate one of the said co-axially aligned portions of said shaft, a gear train connecting the said shaft and said motor means and a means to control said motor.

25 5. A self propelled toy comprising a pair of closed end tubular wheels, a mechanism housing cavity formed within the open ends of said wheels, a shaft adapted to maintain said wheels in a spaced apart rotatable relationship, the said shaft comprising two axially aligned electrically conductive portions, a connector between the said sections adapted to maintain said portions in a spaced apart coaxial alignment and electrical disconnection, a means within one of said portions to contact the other portion within the said connector, a means to conduct electricity to each of said shaft portions, an electric motor power means suspended from said shaft adapted to rotate said shaft, a friction clutch on the outer end of each of said portions adapted to engage the hub of the tubular wheel and a means for moving the said means within said one portion to control flow of electrical current to said motor disposed on the said end of said one of said shaft portions.

30 6. A self propelled toy comprising a pair of closed end tubular wheels, a mechanism housing cavity formed within the said tubular wheels, a shaft adapted to maintain said wheels in a spaced apart rotatable parallel relationship, the said shaft comprising at least two co-axially aligned portions, a friction clutch on one of the said axially aligned portions of said shaft adapted to engage each wheel independently, a motor means suspended from said shaft adapted to rotate one of the said co-axially aligned portions of said shaft, a gear train connecting the said shaft and said motor means and a means to control said motor.

35 7. A self propelled toy comprising a pair of closed end tubular wheels, a mechanism housing cavity formed within the open ends of said wheels, a shaft adapted to maintain said wheels in a spaced apart rotatable relationship, the said shaft comprising two axially aligned electrically conductive portions, a connector between the said sections adapted to maintain said portions in a spaced apart coaxial alignment and electrical disconnection, a means within one of said portions to contact the other portion within the said connector, a means to conduct electricity to each of said shaft portions, an electric motor power means suspended from said shaft adapted to rotate said shaft, a friction clutch on the outer end of each of said portions adapted to engage the hub of the tubular wheel and a means for moving the said means within said one portion to control flow of electrical current to said motor disposed on the said end of said one of said shaft portions.

40 8. A self propelled toy comprising a pair of closed end tubular wheels, a mechanism housing cavity formed within the said tubular wheels, a shaft adapted to maintain said wheels in a spaced apart rotatable parallel relationship, the said shaft comprising at least two co-axially aligned portions, a friction clutch on one of the said axially aligned portions of said shaft adapted to engage each wheel independently, a motor means suspended from said shaft adapted to rotate one of the said co-axially aligned portions of said shaft, a gear train connecting the said shaft and said motor means and a means to control said motor.

45 9. A self propelled toy comprising a pair of closed end tubular wheels, a mechanism housing cavity formed within the open ends of said wheels, a shaft adapted to maintain said wheels in a spaced apart rotatable relationship, the said shaft comprising two axially aligned electrically conductive portions, a connector between the said sections adapted to maintain said portions in a spaced apart coaxial alignment and electrical disconnection, a means within one of said portions to contact the other portion within the said connector, a means to conduct electricity to each of said shaft portions, an electric motor power means suspended from said shaft adapted to rotate said shaft, a friction clutch on the outer end of each of said portions adapted to engage the hub of the tubular wheel and a means for moving the said means within said one portion to control flow of electrical current to said motor disposed on the said end of said one of said shaft portions.
